SNAP SWITCH

Homer E. Malone, Milwaukee, Wis., assignor to
 Perfex Corporation, Milwaukee, Wis., a corporation of Wisconsin

Application May 4, 1945, Serial No. 591,950

8 Claims. (Cl. 200—67)

1

This invention relates in general to switching mechanisms, and more particularly to enclosed snap switches for use in automatic control devices.

It has become common to employ enclosed snap switch mechanisms in automatic controls such as thermostats, pressure controls, etc. These snap switches consist of a snap action contact mechanism mounted in a plastic housing, the switch being actuated by a plunger which extends through one wall of the housing. These switches also have terminals on the outside of the housing for attaching the lead wires to the control. In the snap switch mechanisms now in use, the terminals are located on the side of the switch opposite from the plunger. This arrangement is satisfactory for many applications of the switch in automatic control devices. However, this switching arrangement involves difficulties in design when it is incorporated in many other types of control devices. In these devices it is necessary to locate the switch so that the wiring terminals are accessible to the installer. In many cases this position of the switch in the control involves difficulties in obtaining an actuating mechanism which reaches the switch plunger. Thus in certain applications the switch must be mounted on brackets spaced from the base, and additional mechanism, such as bell cranks, are required to transfer the motion from the condition responsive device to the switch plunger. These additional parts, in addition to increasing the expense of the control, also decrease the sensitivity of the control due to the additional friction which they cause.

The primary object of the present invention is to provide a new type of snap switch mechanism which is especially adaptable to automatic control devices.

In accordance with the present invention the snap switch mechanism is incorporated in a generally rectangular shaped housing which is formed with a terminal panel that extends at an angle to both the base and side walls of the housing. This arrangement spaces the terminal panel from the base of the instrument upon which it is mounted and insures easy access to the terminals, regardless of the position of the switch in the control.

A further object of the invention is to provide an enclosed snap switch mechanism which is short in length. This increases the flexibility in application of the switch.

Other objects will appear as this description proceeds.

2

For a full disclosure of the invention, reference is made to the following description and to the accompanying drawings in which,

Fig. 1 is an external view in perspective of the new type snap switch mounted on a suitable support;

Fig. 2 is a view of the switch housing similar to that shown in Fig. 1, with the support and with wall portions of the housing broken away to better illustrate the construction thereof;

Fig. 3 is a sectional view taken on line 3—3 of Fig. 1 with the contacts shown in open position;

Fig. 4 is a sectional view taken on line 4—4 of Fig. 1;

Fig. 5 is a sectional view taken on line 5—5 of Fig. 4; and

Fig. 6 is a view in perspective of the bell crank supporting bracket; and

Fig. 7 is a view in perspective of the bell crank lever.

Referring to Fig. 1, reference character 1 indicates the switch housing which is generally rectangular in form but which is formed with an angular face 2 disposed in obtuse angle forming relation with respect to the vertical and horizontal wall portions joined therewith. This angular face provides a terminal panel for the switch, this terminal panel including terminal

30 screws 3 and 4. Preferably the terminal panel is formed with a barrier 5 between the terminal screws and with barriers 6 and 7 at the end of the housing. The housing illustrated is shown of two-piece construction, including housing members 8 and 9. The housing member 8 forms a base member for the switch and is L-shaped. This base member at its ends is formed with upstanding bosses 10 and 11 having mounting holes 12 and 13. These mounting holes provide 40 for mounting the switch on a suitable support 14 by means of screws 15.

The housing member 9 is also L-shaped with an angular corner wall forming the terminal panel. This housing member is also formed with end walls 16 and 17. The housing members are held together by means of screws 18 and 19 which extend through the end walls and into alignable internally threaded holes 20 in the bosses 10 and 11 of the housing member 8.

As shown in Fig. 3, the terminal panel section 2 of the housing is formed with a metal insert 20 which is threaded to receive terminal screw 4. This insert 20 is attached as by brazing to a bracket 21 which extends downwardly and which carries a stationary contact stud 22. The ter-

terminal screw 3 fits into a similar insert or bushing (as shown) and is attached to a bracket 23 which receives a contact stud 24. The terminal screws are thus directly connected by brackets 21 and 23 with the stationary contacts 22 and 24.

The stationary contacts cooperate with movable contacts 25 and 26. The contact 25 is directly secured to a contact bar 27. Contact 26 is attached to a leaf spring 28, the other end of this spring being secured to contact bar 27 at contact 26. The contact bar 27 is provided with ears 29 (Fig. 4) which receive a pivot pin 30. This pivot pin is supported between ears 31 of a bell crank member 32. This bell crank member is formed with an armature portion 33 which is located adjacent a permanent magnet 34. The bell crank member 32 is also formed with ears 35 which receive a pivot pin 36 which is supported by ears 37 of a bracket member 38. This bracket member is supported at the back of the terminal panel by means of a screw 39 which extends through the panel. The bracket 38 is formed with a downwardly extending portion 40 which engages the stationary magnet. The bracket 38 thus serves the dual function of supporting the bell crank 32 and holding the permanent magnet in place.

The base member 8 is formed with an opening for receiving an actuating plunger 41. This plunger is formed with a shoulder 42 for limiting outward travel of the plunger. The plunger extends across the interior of the housing and is provided with a stem 43 which is received in a recess 44 formed in the housing member 9. The plunger is also provided with an enlarged portion 45 which receives the lower end of a coil spring 46, the upper end of which bears against the arm 47 of the bell crank lever 32. If desired, the enlarged portion 45 may be made adjustable on the plunger, as by screw threads, so as to provide for adjustment of the initial tension of the coil spring 46.

With the parts in the positions shown, the plunger 41 is in its depressed position, which has placed sufficient tension on the spring 46 to force the armature 33 away from the permanent magnet, thus causing the movable contacts to be disengaged from the stationary contacts. As the plunger 41 recedes, the tension on spring 46 will be eventually reduced to the point at which it is insufficient to overcome the pull of the permanent magnet. When this occurs, the bell crank lever will rotate counter-clockwise as shown in Fig. 4, this motion taking place with a snap action so that the movable contacts are snapped into engagement with the stationary contacts. When the plunger is depressed, the tension on the spring 46 will be gradually increased until it overcomes the attractive force of the magnet. When this occurs, the contacts will open with snap action.

In order to adjust the gap between the armature and magnet when the contacts are closed, the stationary contact studs are formed with hollow sockets 49. This permits the studs to be turned by a wrench which is inserted through openings 48 in the housing which are in alignment with the studs. This arrangement provides for adjusting the switch after it has been completely assembled.

It should be noted that with the angular terminal panel, the panel become accessible from two directions instead of a single direction. This permits a greater variety of mounting positions for the switch and thus increases its flexibility in application.

The construction in which an elongated plunger extends completely across the housing insures that the plunger will not be cocked in operation. In the prior art switches, employing short floating plungers, the plunger can be canted or tilted relative to its slide by the actuator, thereby increasing the friction between the plunger and its guide. The elongated plunger construction provided by the present invention insures that no such canting or tilting can occur and thus increases the sensitivity of the switch.

From the foregoing it will be seen that the present invention provides a simple and compact snap switch mechanism having a terminal panel which is accessible in a large variety of applications of the switch in a control device. While I have shown and described a preferred form of the invention, it is obvious that many changes in construction may be made without departing from the spirit and scope of the invention. It is therefore desired to be limited only by the scope of the appended claims.

What is claimed is:

1. An enclosed snap switch comprising a generally rectangular housing, a stationary contact mounted within said housing, a magnet disposed within said housing in proximity to a wall thereof, a movable contact mounted within said housing for coaction with said stationary contact, a bracket mounted within said housing and including an ear providing a pivot mounting and an extended portion engaging and retainably positioning said magnet against said wall, and a bell crank lever supported by said pivot and having arms embracing an angle, one of said arms having a movable contact facing outwardly with respect to said angle, said lever including an armature part disposed in adjacent operative relation with respect to said magnet and an actuator disposed within said angle and positioned to move said crank in contact movements.

2. An enclosed snap switch comprising a generally rectangular apertured housing including an outer wall portion disposed in obtuse angle forming relation with respect to a pair of spaced walls joined therewith, a pair of terminals mounted in spaced relation on said wall portion, a pair of stationary internal contacts carried by one of said pair of walls in adjacent relation to and connected with said pair of terminals, a magnet disposed between said stationary contacts and adjacent said one wall, a bracket detachably secured to said wall portion and including a first inwardly off-set part affording a pivot mounting and a second inwardly off-set part engaging and retainably positioning said magnet against said one wall, a bell crank supported by said pivot mounting and including an armature arm disposed in adjacent operative relation with respect to said magnet, a contact bar carried by said armature arm in bridgable relation with respect to said stationary contacts, and means guided through the apertures of said housing for actuating said lever so as to move said armature arm toward or away from said magnet.

3. An enclosed snap switch comprising a generally rectangular housing including an outer wall portion disposed in obtuse angle forming relation with respect to a pair of spaced walls joined therewith, a pair of terminals mounted in spaced relation on said wall portion, a pair of stationary internal contacts carried by one of said pair of walls in adjacent relation to and connected with said pair of terminals, a magnet

disposed adjacent said stationary contacts and adjacent said one wall, a bracket detachably secured to said wall portion and affording a pivot mounting and means engaging and retainably positioning said magnet against said one wall, a bell crank supported by said pivot mounting and including an armature arm disposed in adjacent operative relation with respect to said magnet and a second arm disposed in spaced relation with respect to the other of said pair of walls and with respect to a wall of said housing spacedly opposing said other wall, said opposed walls having a pair of openings therein disposed in general alignment with respect to each other, a contact bar carried by said armature arm in bridgible relation with respect to said stationary contacts, a plunger type actuator having opposite end portions disposed in said openings for guided reciprocation therein with one of said end portions accessible for external actuation, and resilient motion transmitting means disposed with the angle of the bell crank operatively connecting an intermediate portion of said actuator with said second lever arm.

4. An enclosed snap switch comprising a generally rectangular housing, a stationary contact mounted on one wall of said housing, a movable contact mounted within said housing for coaction with said stationary contact, a bracket mounted within said housing and including a part providing a pivot mounting, a bell crank supported by said pivot mounting and including a first arm connected in actuating relation with respect to said movable contact and a second arm disposed between two opposed walls of said housing in spaced relation thereto and at right angles to the wall provided with the stationary contact, an elongated actuator extending between and carried by opposed portions of said two walls for guided reciprocation in a direction generally perpendicular with respect to said second lever arm, and resilient motion transmitting means operatively connecting an intermediate portion of said actuator with said second lever arm.

5. A switch including a housing having a contact member, a magnet and a bracket closely adjacent one another and mounted to the housing, a bell crank pivotally mounted on the bracket, said crank having arms embracing an angle away from said contact magnet and bracket, a contact carried by one arm of the crank in juxtaposition to the contact on the housing, and an actuator in the embraced angle and bearing against the other arm.

6. A switch including an apertured housing having a contact member, a magnet and a bracket therewithin, a bell crank pivotally mounted on the bracket, said crank having arms embracing an angle sufficiently small to permit a swinging movement of the crank about its pivotal mounting on the bracket, a contact carried by one arm of the crank in juxtaposition to the contact on the housing, and an actuator receivable for guided movement in the apertures in the housing and provided with a shoulder for engagement with the other arm of the crank to cause contact engaging motion of the crank.

7. A switch including a housing apertured at spaced points and having contact lever and a bracket, a bell crank pivotally mounted on the bracket, said crank having one apertured arm and one contact bearing arm, an actuator extending through the apertures in said housing to be guided thereby, said actuator being shouldered and extended through the aperture in the housing and through said bell crank arm, and resilient means between the shoulder and the said apertured arm.

25 8. A switch including an apertured housing having spaced fixed contacts and a magnet therebetween, a bracket for said housing spaced from said magnet and provided with a pivotal mounting, a bell crank pivotally secured to said bracket and provided with an armature arm and an apertured actuator arm, said arms being disposed at an angle embracing an actuator and a contact carrying contact bar, and a shouldered actuator extending reciprocably into the apertures in the housing and through the apertured bell crank arm with a shoulder in operative relation to said apertured arm, said armature arm being disposed to swing to and from the magnet.
